UNITED STATES PATENT OFFICE.

JOHN EDWARD OGDEN, OF MOUNTAINVILLE, NEW YORK.

CABLE-CLAMP.

1,151,380.

Specification of Letters Patent. Patented Aug. 24, 1915.

Application filed February 17, 1915. Serial No. 8,772.

To all whom it may concern:

Be it known that I, JOHN EDWARD OGDEN, a citizen of the United States of America, and a resident of Mountainville, town of Cornwall, Orange county, and State of New York, have invented certain new and useful Improvements in Cable-Clamps, of which the following is a specification, reference being had to the accompanying drawings, 10 forming a part thereof.

My invention relates to devices for hanging or supporting electric cables and wires along the faces of walls, ceilings, fences, or other structures.

15 One object of my invention is to provide a device of the aforesaid character that shall be simple in construction and which may be produced in large quantities at small expense.

20 Another object is to provide an improved means for attaching the so-called bridle ring to the clamp.

Other objects and advantages of my invention will be set forth hereinafter, and in 25 order that my invention may be thoroughly understood I will now proceed to describe the same in the following specification and then point out the novel features thereof in appended claims.

30 Referring to the drawings: Figure 1 is a side elevation partly in section, of a clamp which embodies my invention, with its bridle ring attached, the wall to which the clamp is attached and the cable supported by 35 the clamp being shown in cross-section. Fig. 2 is a rear elevation of this clamp. Fig. 3 is a longitudinal sectional elevation through the center of the clamp and the bridle ring socket. Fig. 4 is a view corresponding to 40 Fig. 1, of a modified structure which also embodies my invention.

In Patents Nos. 1,060,014-15-16 granted to me on April 29, 1913, I have shown and described cable clamps of the same general 45 character as that to which my present invention pertains. It has been my present aim to produce an inexpensive clamp that shall combine some of the advantages which the several clamps of my previous inventions 50 were intended to secure.

In the carrying out of my invention, I provide an insert of non-rusting metal which is provided with a tapped hole to receive the bridle ring and has an enlargement 55 constituting a laterally extending projection or toe for the clamp.

Referring to Figs. 1, 2 and 3, the clamp comprises a sheet metal strap having a flat portion 10 provided with a hole 11, a curved clamping portion 12, and an insert 14. The 60 clamp may also be provided with a laterally bent toe 13. The insert 14 of non-rusting metal is formed into the clamp as clearly shown in the drawings, has an enlargement 15 constituting a projection or toe, and has 65 a tapped hole 16 to receive a bridle ring 17 of usual form.

As shown in Fig. 4, the laterally bent toe projection may be omitted, the enlargement 15 of the insert performing the function 70 alone.

When the cable line is erected it is often customary to leave off the bridle rings as they are not needed at first. The tapped hole in the clamp is thus exposed to the 75 weather and the metal soon rusts in clamps as ordinarily constructed. With the arrangement of my invention, however, the body of the clamp may be formed of iron or steel strap in the usual manner, but the 80 insert which is relatively small is formed of non-rusting metal such as bronze or brass. It is consequently not damaged by exposure to the weather and is always ready for use. 85

A screw such as 18, extends through the hole 11 which is intermediate the clamping portion 12 (and consequently the bearing point of the cable in the wall), and the part 15 which forms the toe of the device and its 90 support on the wall. This screw consequently secures the clamp in position on the wall or surface 17 to which it is attached and affords a firm support for the cable.

The internally threaded socket is of substantial length,—preferably greater than the thickness of the body portion of the clamp so that a threaded portion of ample length is provided for the reception of the threaded shank of the bridle ring. 95 100

The hanger of my present invention is adapted to receive screw threaded bridle rings of well known form, but the screw threads of the socket are non-rusting. Consequently, I combine in a single clamp the 105 advantages of cheapness and simplicity in construction with durability when subjected to adverse weather conditions.

What I claim is:

1. A hanger for supporting a cable 110 against a wall or similar surface comprising a curved body portion, adapted to partially

encircle the cable, a flat portion adapted to lie parallel with the surface, and a socket-
insert of non-rustable metal adapted to receive a bridle ring and having an enlargement constituting a laterally extending toe or projection for the clamp.

2. A hanger for supporting a cable against a wall or similar surface comprising a curved body portion, adapted to partially encircle the cable, a flat portion adapted to lie parallel with the surface, and a laterally extending toe or projection embodying a socket insert of non-rustable metal having a tapped hole and adapted to receive a bridle ring.

3. A hanger for supporting a cable against a wall or similar surface comprising a curved body portion, adapted to partially encircle the cable, a flat portion adapted to lie parallel with the surface, and a laterally extending toe or projection adapted to engage the wall or surface, and an internally threaded socket insert of greater length than the thickness of the body portion, of non-resistible material adjacent to the toe projection and adapted to receive a bridle ring, said flat portion of the clamp having a hole intermediate the curved portion of the clamp and said toe through which a

screw may extend to fasten the clamp in position.

4. A hanger for supporting a cable against a wall or similar surface comprising a curved body portion, adapted to partially encircle the cable, a flat portion adapted to lie parallel with the surface, and a socket-
insert adapted to receive a bridle ring and having an enlargement constituting a laterally extending toe or projection for the clamp.

5. A hanger for supporting a cable against a wall or similar surface, comprising a body portion adapted to partially encircle the cable, a flat portion adapted to lie parallel with the surface, and a non-rustable socket member carried by the flat portion, adapted to receive a bridle ring and having an enlargement constituting a laterally extending toe or projection for the clamp.

In testimony whereof, I have hereunto set my hand this 11th day of February, 1915, in the presence of two subscribing witnesses.

JOHN EDWARD OGDEN.
